UNITED STATES PATENT OFFICE.

KATIE POMMER, OF BEMIDJI, MINNESOTA.

INCUBATOR ATTACHMENT.

Application filed August 18, 1925. Serial No. 50,988.

To all whom it may concern:

Be it known that KATIE POMMER, a citizen of the United States, residing at Bemidji, in the county of Beltrami and State of Minnesota, has invented certain new and useful Improvements in an Incubator Attachment, of which the following is a specification.

The present invention relates to an incubator attachment and has for its principal object to provide a structure whereby it is possible to remove dry chicks from an incubator without changing the temperature inside the incubator.

Another important object of the invention is to provide an attachment of this nature which may be easily and quickly associated with the incubator and which embodies a heating element in the form of a hot water tank so that when the interior of the attachment is in communication with the interior of the incubator no cool air will be allowed to pass into the incubator.

At the present time it is most common to remove the dry chicks from the incubator by hand. In this practice considerable cool air is allowed to enter the incubator so that the chicks which hatch out later are frequently weak and sickly owing to the fact that the temperature of the incubator is too low for the wet chicks. My invention effectively overcomes these undesirable features of the present common method.

A still further very important object of the invention is to provide an attachment of this nature which is exceedingly simple in its construction, strong, durable, easy to manipulate, effective and reliable in use, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing,

Figure 1 is a sectional view taken longitudinally through the attachment and a portion of an incubator, and

Figure 2 is a transverse section through the attachment.

Referring to the drawing in detail it will be seen that numeral 5 designates generally a box-like casing having one end closed by

a transparency 6, while the other end is open. The casing 5 is divided into compartments 7 and 8 by a removable partition 9 slidable through the top of the casing, suitable self-packing 10 being utilized to prevent air from escaping between the top wall and the said slidable partition. The partition is slidable in channeled cleats 11 arranged vertically on the sides of the casing interiorly thereof. An inverted L-shaped bracket arm 12 is attached in any suitable manner to the casing 5 and extends upwardly therefrom for engagement over the top of an incubator A. L-shaped bracket arms 13 depend from the casing 5 and have screws 14 threaded through the ends thereof. Shoes 15 are provided on the ends of the screws for engaging the bottom of the incubator A. It will thus be seen that the attachment may be readily associated with the end of the incubator so as to be supported thereon. The end of the incubator A to which the attachment is mounted is provided with a hingedly mounted door 16 which may be opened into the compartment 7 as is clearly shown in Figure 1. When the attachment is in place access may be had to the door 16 for opening and closing the same, through a hinged door 18. A hot water tank 19 is situated in the top of compartment 8 and has a filling spout 20 rising therefrom upwardly through the top of the casing. The tank 19 extends to a point spaced above the bottom of compartment 8 and thus the chicks in the incubator may see light from the bottom of the glass wall 6 and thus be attracted into the attachment. The attachment is put in place on the incubator after the tank 19 has been filled with hot water and the partition 9 is opened or raised so as to give the air in the attachment an opportunity of circulating and becoming of an even temperature, that is, to become heated from the tank 19. The door 18 may then be opened for opening the door 16. The chicks which have become dry will then naturally step out into the attachment on the incubator. The door 16 may then be closed and the attachment removed so that the chicks may be placed in a brooder or any other desirable place.

The present embodiment of the invention has been disclosed merely by way of example, since in actual practice it attains the features of advantage enumerated as

desirable in the statement of the invention and the above description. It will be apparent that numerous changes in the details of construction and in the combination and arrangements of parts may be resorted to without departing from the spirit or scope of the invention as hereinafter claimed or sacrificing any of its advantages.

Having thus described my invention what I claim as new is:

- 10 1. An attachment for incubators including a box-like structure having one end closed with a transparency and the other end open, and a heating element in the casing adjacent the closed end.
- 15 2. An attachment for incubators including a box-like structure having one end closed with a transparency and the other end open, and a heating element in the casing adjacent the closed end, and means for closing the portion of the casing in which is disposed the heating element from the remaining portion thereof.
- 20 3. An attachment for incubators including a casing having an open end and a closed end, the latter having a transparency therein, and a heating element located in the casing adjacent the transparency, and a par-

tion slideable transversely of the casing to shut off the heating element from the remaining portion of the casing.

4. An attachment for incubators including a casing having an open end and a closed end, the latter having a transparency therein, a heating element located in the casing adjacent the transparency, and a partition slideable transversely of the casing to shut off the heating element from the remaining portion of the casing, and a door hinged in the casing adjacent the open end thereof.

5. An attachment for an incubator, wherein the incubator is provided with an end wall having an opening and a hinged closure for said opening, comprising a box-like structure having an open end and a closed end, the latter end including a transparency, a hot water tank located in the casing adjacent the transparency, a partition slideable transversely across the interior of the casing, a door hingedly mounted adjacent the open end of the casing, and means for attaching the open end of the casing over the opening in the incubator.

In testimony whereof I affix my signature.

KATIE POMMER.
